UNITED STATES PATENT OFFICE.

WALTER J. BELL, OF LOS ANGELES, CALIFORNIA.

STERILIZER.

1,032,647.

Patented July 16, 1912.

Application filed January 2, 1912. Serial No. 669,120.

To all whom it may concern:

Be it known that I, WALTER J. BELL, a citizen of the United States, residing at the city of Los Angeles, county of Los Angeles, and State of California, have invented new and useful Improvements in Sterilizers, of which the following is a specification.

My invention relates to a vessel electrically heated for raising water or other liquid to a temperature that will sterilize dental, surgical and other instruments, and the object thereof is to produce a sterilizer in which the liquid may be quickly heated to the sterilizing point and which will automatically break the circuit of the heating element in case the liquid should be evaporated from the vessel to a certain predetermined level thus preventing injury to the liquid receptacle. I accomplish this object by the device described herein and illustrated in the accompanying drawings, in which;

Figure 1 is a fragmentary side elevation with parts broken away for clearness of illustration. Fig. 2 is an end elevation of the base, and a cross section of the sterilizing tank, on the line 2—2 of Fig. 1. Fig. 3 is a diagrammatic view of the wiring and connection of parts. Fig. 4 is a cross section of the solenoid.

10 In the drawings 10 is a rectangular vessel preferably of sheet metal and 11 is a removable cover for the same. The bottom 13 is corrugated to form troughs 14. At one end these troughs have sloping ends that slope 15 downwardly to the bottom as shown in Fig.

1 so that the liquid in the vessel can circulate evenly between the corrugations. Extending transversely to the vessel at each end thereof are bars 15 of insulating material to which are secured the major heating coils 16 which are connected in series. These coils extend through the troughs in the bottom and are insulated therefrom by sheet asbestos 19. One end of these coils is connected to the return wire 17 and the other end is connected to contact 18. Adjacent to bars 15 are bars 20 likewise of insulating material to which are connected minor coils 21, which are insulated from the major coils by a sheet 20 of asbestos 22. These coils are connected in series and are also connected at one end to contact 23 and at the other end to contact 18.

A sheet of metal 23 is secured to the vessel and supports the coils. This metal sheet is 55 insulated from the minor coils by a sheet of

asbestos 24. The feed wire 25 is connected to contact spring 26 which spring is secured to the base 27. The base is preferably of insulating material but if not of insulating material, the feed wire and all contacts are 60 insulated therefrom. A like and oppositely disposed contact spring 28 is also secured to the base. Contact spring 28 is connected to contact 29 and also to the coils of the solenoid magnet 30:

65 A switch 29 is carried by contact 29 which can be turned so as to connect either contact 23 or 18 and thereby utilize both coils or only the major coils. The plunger of the magnet is composed of an iron rod 31 which 70 projects in front of the coils and carries a contact ring 32 which is insulated from the rod. This contact ring normally engages contact springs 26 and 28. The iron rod extends normally to about the center of the 75 coils and is there connected to a brass rod 33 which normally extends to the surface of the base. The other end of the coils of the solenoid is connected to a contact 34 which is secured to the end of float tank 35. A like 80 contact 36 is secured to the other end of the float tank and is connected to the return wire. Near the bottom of the float tank is a port 37 and near the top thereof is a port 38. These ports connect the float tank with the 85 sterilizing tank so that the liquid level is always the same in both. In the float tank is a float 39 which is preferably cylindrical in shape. At each end of the float are wires 40 which have an adjusting curve 41 near 90 the top thereof. Wires 40 are connected to a cross bar or wire 42 which cross bar connects contacts 34 and 36 when the liquid in the tanks falls below a certain predetermined level and thereby closes the shunt circuit which energizes the magnet.

95 As soon as the magnet is energized the plunger withdraws contact ring 32 from its engagement with contact springs 26 and 28 and the main circuit as well as the shunt circuit is opened and the current to the instrument is automatically broken thereby preventing injury thereto. When the tanks are refilled the float opens the shunt circuit and the operator pushes the core of the magnet 100 to its normal position thereby closing the main circuit when the instrument is again ready for use.

105 While I have shown my device applied as a sterilizing device it may be used in evap-

orating any liquids and will act automatically to cut off the heat when the liquid reaches a predetermined level. The float could be located within the main chamber if desired but is placed within a connected float chamber to be out of the way when the main chamber is being utilized.

Having described my invention what I claim is;

- 10 1. In a liquid evaporating device, heating means comprising a liquid evaporating tank; resistance coils for heating the contents of the tank, a normally closed circuit for operating the resistance coils, said circuit having a movable switch for breaking the same; a normally open shunt circuit connected with the main circuit and having a magnet therein, said magnet being connected to the switch in the main circuit; and means 15 operable by the fall of liquid in the tank to

close the shunt circuit whereby the main and shunt circuit are both broken.

2. In a liquid evaporating device, a liquid evaporating tank; electrical means for heating the contents thereof comprising major and minor coils; means for connecting and disconnecting the minor coils from the major coils, a main circuit for operating said coils; a normally open shunt circuit connected to the main circuit; and means operable by the fall of liquid in the tank to close the shunt circuit and open both the main and shunt circuits.

In witness that I claim the foregoing I have hereunto subscribed my name this 23rd day of December, 1911.

WALTER J. BELI.
